HINGE CONSTRUCTION

Harry S. Bradley, West Haven, Conn.

Application December 26, 1945, Serial No. 637,147

5 Claims. (Cl. 16—137)

1

This invention relates to a hinge construction, and more particularly to the provision of a hinge which shall be weatherproof, whether the hinge member is in open or closed position.

In many locations, such, for example, as in windshields and skylights for the cabins of boats, it is necessary to hinge the windows so that they can be opened. This hinged joint between the movable and stationary members of the windshield and skylight has been a source of trouble in that it is apt to leak and permit rain or moisture from other sources to pass therethrough.

I contemplate by the present invention the provision of a hinge which may be used in locations where it is desired to make a waterproof hinge joint, it being understood that it is not limited to the particular locations mentioned above, the hinge being so constructed that it may be freely operated and easily installed. In order to effect this result, I secure under the leaf portion of one of the two members of the hinge a thin plate of smooth sheet material, such as sheet metal, this plate extending freely into a space below the leaf of the cooperating hinge member so as to have sliding movement with respect thereto. This plate member extends across the joint or pintle of the hinge, so that it completely seals the joint and also makes tight, although sliding, contact between the leaf of the hinge and the window or window frame so as to make a tight joint.

One object of the present invention is to provide a weatherproof hinge of novel construction.

Another object of the present invention is to provide a weatherproof hinge wherein a thin flexible plate member is secured to one of the hinge members or to the support for such hinge member and extends across the joint of the hinge to make close contact with the cooperating hinge structure so as to completely seal the hinge joint.

A still further object of the invention is to provide a weatherproof hinge structure wherein a thin sheet or plate is connected to each of the portions of the hinge and extended across the hinge joint, these plates overlapping and having sliding contact with each other during relative movement of the two portions of the hinge and making tight contact with each other whereby effectually to seal the hinge joint.

To these and other ends the invention consists in the novel features and combinations of parts to be hereinafter described and claimed.

In the accompanying drawings:

Fig. 1 is a front elevational view of a window

2

or windshield of a boat cabin provided with a hinge embodying my invention;

Fig. 2 is an enlarged sectional view on line 2—2 of Fig. 1, the window being shown in closed position;

Fig. 3 is a view similar to Fig. 2, the parts being shown in the open position of the window;

Fig. 4 is a view similar to Fig. 2 showing a modified form of my device;

Fig. 5 is a view similar to Fig. 2 showing a further modification; and

Fig. 6 is a fragmentary perspective view of one of the sealing plates.

To illustrate a preferred embodiment of my invention, I have shown in Fig. 1 of the drawings a fixed frame or casing 10 to which is hinged a windshield or window 11 by the hinge structure designated generally by the numeral 12, so that the window may swing outwardly about the joint of the hinge in a well-known manner.

As shown in Fig. 2, the hinge member itself may be of conventional form comprising, for example, hinge leaves 13 and 14, these members being provided with registering knuckles 15 to receive a hinge pin or pintle 16. The two parts of the hinge 13 and 14 may be secured to the fixed and movable members 10 and 11, respectively, by any desired means, such as the screws 17 and 18.

In order to provide a weatherproof joint between the parts 10 and 11, I have shown in Figs. 2 and 3 of the drawings a plate member 19 made of thin flexible material. This member may be conveniently made of sheet metal, so that it will have a smooth surface and will slide freely relatively to the other parts of the structure as will be hereinafter explained. This member may be secured to the part 13 of the hinge by having the screw 17 pass through an opening therein and, as shown at 20, is folded upon itself at one end to provide a spacing member 21 to space the plate or sheet member 19 from the frame 10.

Likewise, a plate member 22, similar in all respects to the plate 19, is secured to the other leaf 14 of the hinge, this plate having a spacing member 23 disposed between the body portion thereof and the leaf of the hinge. It will be noted that the members 19 and 22 extend freely from their secured ends beyond the pintle or joint of the hinge and into the spaces provided by the spacing members 21 and 23. One of these plates—the plate 19—as shown lies adjacent the hinge leaves and slides between the hinge and the other plate,

while the plate 22 lies between the plate 19 and the fixed and movable frames 13 and 14.

In order to facilitate free sliding movement of the plates 19 and 22, and particularly the latter, when the window or windshield is opened and closed, smooth plates of metal, or a suitable material, 25 and 26 may be secured to the fixed and movable frames, the plate 25 lying below the spacing member 21 and, as shown in Fig. 3, providing a space between it and the body of the plate 19 for reception of the end of the plate 22 while the plate 26 lies immediately below the member 22.

The closed position of the parts is shown in Fig. 2 where, as will be seen, the sealing plates 19 and 22 both extend across the hinge joint in overlapping relation and make tight contact with each other and with the adjacent parts of the hinge to seal the joint. These sealing plates are flexible and may be made of very thin material, so that they will flex readily when the window is moved to open position as shown in Fig. 3 and move outwardly in a separating direction, their ends, however, remaining within the spaces or channels provided for these ends so that they will slide back in place when the window is closed. I have found that this makes a very effective seal and adds but little to the cost of the hinge and does not interfere with its free operation.

In Fig. 4 of the drawings I have shown a slightly modified form of structure which, in all respects, is like that described in connection with Figs. 1 to 3 of the drawings, except that a pair of additional plates 27 and 28 are secured below the leaves 13 and 14 of the hinge. These plates may be quite thin and are preferably of thin sheet metal, so that the sealing plate 19 may slide freely thereon. These plates 27 and 28 may or may not be necessary, depending upon whether or not the lower surfaces of the leaves 13 and 14 are sufficiently smooth to permit the proper operation of the parts. In some instances, the surfaces of these leaves as manufactured are not smooth, and in such case the thin plates 27 and 28 may be inserted to provide for free sliding movement of the outer plate 19.

In Fig. 5 of the drawings I have shown a further modification in which a single sealing plate 19^a is provided, which plate is secured to the leaf 13. The other leaf 14 of the hinge may be spaced from the plate 26 by a spacing member 30 so as to provide for the reception of the free end of the sealing plate 19^a between the leaf 14 and the plate 26. If desired, plates 27 and 28 may also be used between the plate 19 and the leaves 13 and 14, and the spacing member 30 may be conveniently made by folding upon itself one end of the member 28. It will be seen that the form of my invention shown in Fig. 5 is similar to that shown in Fig. 4 except that only one sealing plate is employed instead of the two employed in the construction shown in the latter figure.

As shown in the drawings my improvements are applied to a hinge, the leaves of which stand substantially in the same plane when the closure member is in closed position and which stand at 90° to each other when the closure member is in full open position.

While I have shown and described some preferred embodiments of my invention, it will be understood that it is not to be limited to all of

the details shown, but is capable of modification and variation within the spirit of the invention or the scope of the claims.

What I claim is:

1. A hinge comprising leaves adapted to be secured to relatively fixed and movable members, a pivot connecting said leaves, a flexible sealing strip having one edge secured between one of the leaves and the member to which the leaf is secured and having a free edge extending across the pivot, and means providing a space between the other hinge leaf and the member to which it is secured, said free edge being slidably and snugly received in said space.

2. A hinge comprising leaves adapted to be secured to relatively fixed and movable members, a pivot connecting said leaves, and a pair of flexible sealing strips each being secured to one of said leaves and having a free edge extending across the pivot and slidably received between the other leaf and the member to which it is secured, said free edges overlapping each other.

3. A hinge comprising leaves adapted to be secured to relatively fixed and movable members, a pivot connecting said leaves, and a pair of flexible sealing strips each being secured to one of said leaves and having a free edge extending across the pivot and slidably received between the other leaf and the member to which it is secured, said free edges overlapping each other, and each of said strips having an end portion folded upon itself and said portion lying opposite the free edge of the other strip.

4. A hinge comprising leaves adapted to be secured to relatively fixed and movable members, a pivot connecting said leaves, a pair of flexible sealing strips each being secured to one of said leaves and having a free edge extending across the pivot and slidably received between the other leaf and the member to which it is secured, said free edges overlapping each other, and a plate secured to each of the fixed and movable members, and said strips lying between said leaves and said plates.

5. A hinge comprising leaves adapted to be secured to relatively fixed and movable members, a pivot connecting said leaves, a flexible sealing strip secured to one of said leaves and having a free edge extending across the pivot and slidably received between the other leaf and the member to which the latter is secured, a plate secured to each of the members and disposed on the side of said strip opposite the leaves, and a spacing member spacing one of said plates from the leaves to provide a space within which said free edge may extend.
